UNITED STATES PATENT OFFICE.

ROBERT E. ADREON, OF ST. LOUIS, MISSOURI, ASSIGNOR, BY MESNE ASSIGNMENTS, TO THE WESTINGHOUSE AIR BRAKE COMPANY, OF WILMERDING, PENNSYLVANIA, A CORPORATION OF PENNSYLVANIA.

AUTOMATIC TRAIN-PIPE CONNECTOR.

1,276,306.

Specification of Letters Patent. Patented Aug. 20, 1918.

Application filed October 6, 1916. Serial No. 124,029.

To all whom it may concern:

Be it known that I, ROBERT E. ADREON, a citizen of the United States, residing at St. Louis, in the State of Missouri, have invented a certain new and useful Improvement in Automatic Train-Pipe Connectors, of which improvement the following is a specification.

This invention relates to devices for coupling train pipes between the cars of a train automatically, and has for its object to provide an improved device of this character which shall be automatically advanced or projected outward when the two cars come together in the act of coupling, and be withdrawn when the cars are uncoupled and pulled apart.

With the present form of automatic train pipe couplings, as heretofore used, the abutting connector heads normally stand some distance in advance of the draw bar and are subjected to damaging blows and rough treatment during the shifting and coupling of cars, while, according to my improvement, the normal position of the connector head is some distance back where it is protected, and does not engage with the counter part connector on the adjacent car that is being coupled up, until the coupling of the draw bars is nearly completed.

In the accompanying drawing: Figure 1 is a plan of a portion of the end of a car frame with parts broken away and showing a portion of the connector device in horizontal section; Fig. 2, a vertical longitudinal section of the same, with portions indicated in elevation; and, Fig. 3, an end elevation.

According to the construction shown, the train pipe connector head, 4, is provided with gathering arms, 4^a, and pipe connections, 4^b, and is mounted to have a pivotal movement and a longitudinal adjustment in the hanger, 5, attached to the draw bar, 6. The hanger may be of a yoke shape having two side bars carrying a horizontal pin, 7, on which is mounted a slideable yoke, 8, at the forward end of which the connector head, 4, is pivotally attached by means of a lug, 9, and a vertical pin, 10. In this way, the connector head has both horizontal and vertical swinging movements, and with the yoke, 8, may be adjusted or moved longitudinally through the hanger.

According to my improvement, this longitudinal movement of the connector head is effected automatically by the coming together and the separation of the cars in the act of coupling and uncoupling, and for this purpose the yoke, 8, is provided with a stem, 11, connected by a chain, 12, to one end of a lever, 13, pivotally mounted on the draw bar and having its upper end connected by a chain, 14, with the platform buffer, 15, having springs, 16. A spring, 18, normally tends to project the connector head outward to its advanced or coupled position, and this spring may be conveniently mounted on the stem, 11, between the yoke 8, and an abutment carried by the hanger or draw bar, this abutment being shown in the form of a yoke, 17, pivotally mounted on the pin, 7, on the hanger.

The springs, 16, of the platform buffer are of greater strength than the connector spring, 18, so that when the cars are uncoupled, the platform buffer is extended and the lever, 13, is actuated to withdraw the connector head to its inner protected position, as indicated in full lines, with the spring, 18, compressed. In this position the connector head is located back of the outer end of the draw bar coupler, and is not exposed to damage from premature contact with the other connector head during the rough handling and attempted coupling of the cars.

When the cars are brought together in the act of coupling, and the platform buffers are forced inward to compress the springs, 16, the spring, 18, is then free to expand and project the connector head outward to the coupled position, also turning the lever, 13, to the position indicated in dotted lines. During this movement, the gathering arms of the counterpart connector heads engage each other and the heads are coupled together. As the yoke, 8, slides forward on the pin, 7, additional freedom of vertical and lateral movement of the connector head is obtained due to the form of the yoke which preferably provides a wider space between the arms toward the rear than at the forward end where the space is about equal to the diameter of the pin, 7.

When the cars are uncoupled and separated, the springs, 16, of the platform buffers expand to move the buffers outward

and withdraw the yoke and connector heads to the inner uncoupled position.

As the connector heads do not come into engagement until the coupling of the draw bars has been very nearly completed, it will not be necessary to have a wide gathering range, consequently the gathering arms may be made much shorter than those heretofore used, and the construction otherwise simplified.

Having now described my invention, what I claim as new and desire to secure by Letters Patent is:

1. In an automatic train pipe connector, the combination of a longitudinally movable connector head, a support therefor, a buffer actuated by the coming together of the cars, and connecting means controlled by said buffer for effecting a longitudinal movement 20 of the connector head, said means including relatively movable parts whereby the connector head may have an independent movement after the buffer is compressed.

2. In an automatic train pipe connector, the combination of a longitudinally movable connector head, a hanger attached to the draw bar for supporting said head, a buffer separate from the draw bar, and means operated by the buffer for shifting said connector 30 head.

3. In an automatic train pipe connector, the combination of a longitudinally movable connector head, a hanger for supporting said head, a yielding buffer, and a spring controlled by the yielding movement of the buffer for projecting said connector head forward.

4. In an automatic train pipe connector, the combination of a longitudinally movable 40 connector head, a hanger for supporting said head, a spring actuated buffer, and means

operated by the outward movement of the buffer for withdrawing said connector head.

5. In an automatic train pipe connector, the combination of a longitudinally movable 45 connector head, a hanger attached to the draw bar for supporting said head, a spring actuated buffer, and means operated by the yielding movement of the buffer for projecting the connector head and by the outward movement of the buffer for withdrawing the connector head.

6. In an automatic train pipe connector, the combination of a longitudinally movable 55 connector head, a hanger attached to the draw bar for supporting said head, a spring actuated buffer, a lever pivotally mounted on the draw bar, a connection from one end of the lever to the buffer, and a connection from the other end of said lever to the connector head.

7. In an automatic train pipe connector, the combination of a hanger attached to the draw bar, and having a horizontal pin, a yoke slidably mounted on said pin, a connector head connected to the forward end of said yoke by a vertical pivot, another yoke secured to the hanger and a spring between said yokes for forcing said yoke forward 70 on said pin.

8. In an automatic train pipe connector, the combination of a hanger attached to the draw bar, a yoke slidably mounted on said hanger, a connector head pivotally connected to the forward end of said yoke, a spring 75 for forcing the yoke and connector head forward, a spring actuated buffer, and a connection from said buffer for withdrawing the yoke and connector head.

In testimony whereof I have hereunto set 80 my hand.

ROBERT E. ADREON.
